SUN SHADE

John D. Penny, 368 N. 15th St., Apt. F, Las Vegas, Nev.

Filed Aug. 9, 1960, Ser. No. 61,682

Term of patent 14 years

(Cl. D88—3)

FIG. 1 is a top plan view of a sun shade, embodying my new design;

FIG. 2 is a side elevational view; and

FIG. 3 is a bottom view thereof taken on the line 3—3 of FIG. 2.

I claim:

The ornamental design for a sun shade, as shown.
